UNITED STATES PATENT OFFICE.

THOMAS P. ARCHER, ERNEST E. HEINTZ, AND FRANK M. EDGAR, OF DETROIT, MICHIGAN, ASSIGNORS TO TERNSTEDT MANUFACTURING COMPANY, OF DETROIT, MICHIGAN, A CORPORATION OF MICHIGAN.

WINDSHIELD REGULATOR.

Application filed December 19, 1924. Serial No. 757,063.

This invention relates to window regulators and especially a window regulator arranged to lift a relatively wide, heavy panel by drawing the same up and thrusting it down.

In the prior Simpson application Serial No. 702,753, a window regulator is described and claimed in its broad aspects for accomplishing the purposes here in view. It is the object of the present invention to provide another type of regulator of this type but which is believed to be an improvement over the Simpson invention in that it has a more positive action and it eliminates completely the cable. This cable has introduced a number of problems and difficulties due to stretching, etc.

In the drawings:

Fig. 1 is a cross section through the top of a closed body, showing an inside elevation of the header and indicating in dotted lines the regulator.

Fig. 2 is a section on the line 2—2 of Fig. 1.

Fig. 3 is an enlarged elevation of the driving end of the regulator with parts broken away.

Fig. 4 is a section taken on the line 4—4 of Fig. 3.

Fig. 5 is a detail of the upper end of the panel, showing the regulator connection.

a designates the roof of the car; *b* the removable header panel. A window guide *c*, either of felt or rubber, covered with an anti-friction material, is provided in the windshield post, a sliding glass panel *e* is raised and lowered by the window regulator. This window regulator is provided with a pair of driven gears or wheels *f* and *g*, carried on a pair of supporting plates *h* and *i*, which are connected by a spacing strip *j*. Riveted to each one of these driven gears is a crank arm *f*¹ and *g*¹, carrying crank pins *f*² and *g*², these engage in the loops *k* secured to the tops of the windshield panel and can slide longitudinally of the panel in the said loops.

The driving effort is communicated from a handle *m* to a spindle *n* and thence through a coil spring clutch *o*, to the driving pinion *q*. It is unnecessary to detail this clutch construction, as the clutch per se is old, and for that matter, numerous forms

of clutches could be used for the purpose, the idea being simply that turning effort originating in the handle releases the clutch and turns the driving pinion; while turning effort originating in the gears and coming through in the reverse direction locks the clutch. This is common construction in all window regulators.

The driving pinion *q* meshes with a gear reducing set including the larger gear *p* and the smaller driving pinion *r*. This driving pinion *r* is a double purpose gear; it meshes with the driven gear *f* and also with the sliding rack *s*. This sliding rack at the opposite end meshes with the driven gear *g*. The interposition of the double purpose driven speed reducing pinion *r* serves also to reverse the direction of movement between the driven gears *f* and *g*. This is a valuable feature as it causes the thrust of the cranks on the panel to neutralize each other.

The spiral counterbalancing spring *t* is associated with the driven gear *g*, having its inner end anchored to the stud shaft of the gear and its outer end to a struck-out lug *u* in the supporting plate.

The sliding rack is suitably guided in the turning over channels *v* and *w* in the supporting plates. These channels support the sliding rack, which meshes with the two gears. The cover plates *y* which fit over the gears are provided with bow springs *z* for rubbing against the rack to prevent rattling. In order to reduce the friction, the regulator plates have punched out portions 1 to form point contacts between the sliding rack and the plate. There is considerable speed reduction between the handle and the driven or lifting gears. This enables the relatively heavy windshield panel to be lifted without a great deal of effort on the part of the operator, although he will have to turn the crank around several times to get the necessary travel.

The rack is quite an improvement over the old cross cable arrangement in that it provides a rigid draft and thrust member. This being firmly held at both ends does not lash back and forth in the header well and hence requires no devices to take care of such lashing action. It will not stretch and consequently there is no slack in the mecha-

nism and the window is therefore instantly responsive to any turning effort. Furthermore, the rack cannot break as it is fully strong enough to take any and all strains 5 and never wear out.

What we claim is:

1. In a window regulator, the combination of two horizontally spaced supporting plates, panel pull-up members on each plate 10 and disposed parallel with the plates, and a positive thrust and draft driving connection between the panel pull-up members.
2. In a window regulator, panel pull-up members horizontally spaced at widely separated points and arranged so as to operate 15 when in position in the plane of the window pocket, and a reciprocating positive thrust and draft driving connection between the panel pull-up members.
3. In a window regulator, a pair of panel lifting wheels horizontally spaced at widely separated points and each arranged for separate engagement with the panel, and a positive thrust and draft connection between 25 the panel lifting wheels, which is arranged also to reversely drive the wheels at the same time.
4. In a window regulator, a couple of panel pull-up wheels horizontally spaced at 30 widely separated points and each having a crank and pin connection with the top of the window panel, and a positive push-and-pull reciprocating driving connection between the two panel pull-up wheels.
5. In a window regulator, the combination of a pair of panel lifting gears at 35 widely separated horizontal points, each provided with a lifting connection with the panel, driving gears for one panel lifting gear including speed reduction means, and 40 a sliding rack connecting with the driving gears and joining the two panel gears for communicating the driving effort and reversing the same as to the two panel lifting gears. 45
6. In a window regulator, the combination of a pair of supporting plates spaced horizontally at widely separated points by a spacer bar, panel-lifting gears supported on each plate and having each a separate 50 connection with the panel, and a horizontally reciprocating sliding rack guided on said plates and connecting the gears for transmitting the driving effort. 55
7. In a window regulator, the combination of a pair of supporting plates spaced horizontally at widely separated points by a spacer bar, panel-lifting gears supported on each plate and having each a separate connection with the panel, a horizontally reciprocating sliding rack guided on said plates and connecting the gears for transmitting the driving effort, and means bearing yieldingly against the sliding rack to 60 prevent rattling. 65
8. In a window regulator, the combination of a pair of supporting plates provided with punched out points, panel-lifting gears supported on the plates at widely separated points, a horizontally reciprocating rack 70 guided in said plates on said points, and yielding means pressing the rack against the points. 75

In testimony whereof we have affixed our signatures.

THOMAS P. ARCHER.
ERNEST E. HEINTZ.
FRANK M. EDGAR.
